ATOMIZER

Sophie Frydlender, Paris, France, assignor to
Lancome, S. A., Paris, France, a corpora-
tion of France

Application January 30, 1952, Serial No. 18,306

Term of patent 7 years

(Cl. D83—1)

To all whom it may concern:

Be it known that I, Sophie Frydlender, a citizen of France and resident of Paris, Department of Seine, Republic of France, have invented a new, original, and ornamental Design for an Atomizer, of which the following is a specification, reference being had to the accompanying drawing, forming a part hereof.

Figure 1 is a perspective view of an atomizer, showing my new design;

Figure 2 is a plan view of the same;

Figure 3 is a side elevation of the same; and
Figure 4 is an end elevation as seen from the left side of Figure 3.

I claim:

The ornamental design for an atomizer, as shown.

SOPHIE FRYDLENDER.
